(57) **CLAIM**

The ornamental design for an electrical connection plug, as shown and described.

DESCRIPTION

FIG. 1 is a front-right-top perspective view of an electrical connection plug showing our new design;

FIG. 2 is a right-end view thereof;

FIG. 3 is a front view thereof;

FIG. 4 is a top view thereof;

FIG. 5 is a rear view thereof;

FIG. 6 is a bottom view thereof; and,

FIG. 7 is a left-end view thereof.

The broken lines in the drawings illustrate portions of the electrical connection plug that form no part of the claimed design.
